UNITED STATES PATENT OFFICE.

ANDREW J. CROPP, OF CHICAGO, ILLINOIS.

MIXING-MACHINE.

1,223,314.

Specification of Letters Patent. Patented Apr. 17, 1917.

Application filed November 29, 1911. Serial No. 663,061.

To all whom it may concern:

Be it known that I, ANDREW J. CROPP, a citizen of the United States, residing at Chicago, in the county of Cook and State of Illinois, have invented certain new and useful Improvements in Mixing-Machines, of which the following is a specification.

This invention relates to improvements in an apparatus which is intended for use in mixing ingredients or materials employed in the production of concrete for any of the purposes for which it may be used, and of that class of such machines in which a rotary drum is adapted to receive the material to be mixed, and which drum is provided internally with means to agitate and mix the material, the same being fed into the drum at one of its ends and discharged therefrom at its other end, and it consists in certain peculiarities of the construction, novel arrangement and operation of the various parts thereof, as will be hereinafter more fully set forth and specifically claimed.

The invention has for its objects to provide a machine of the above mentioned general character, which shall be simple in construction, strong, and durable, and which shall have embodied therein means for efficiently and conveniently charging, for thoroughly performing the operation of mixing and for discharging the mixture when desired and in suitable quantities.

Another object is to provide means for permitting the drum to be charged at a very low point, yet in such a manner, that the slushy material will not work out of the charging end of the drum to clog its gear and retard its rotation and so that a large opening will be provided at the front end of the drum to permit of an inner view thereof so that the operator can watch the mixture and operation of the parts of the machine.

Other objects and advantages of the invention will be disclosed in the subjoined description and explanation.

In order to enable others skilled in the art to which the invention pertains, to make and use the same, I will now proceed to describe it referring to the accompanying drawings in which—

Figure 1, is a sectional perspective view of a machine embodying the invention, the section being taken on line 1—1, of Fig. 2, 55 of the drawings.

Fig. 2, is a front end view of the machine.

Fig. 3, is a fragmental sectional view taken on line 3^a—3^a, of Fig. 2, looking in the direction indicated by the arrows marked 3—3, showing a portion of the rotary drum 60 and the charging chute therefor.

Fig. 4, is a similar view of like parts taken on line 3^a—3^a, of Fig. 2, looking in the direction indicated by the arrows marked 4—4.

Fig. 5, is a plan sectional view of a portion of the machine taken on line 5—5, of Fig. 6.

Fig. 6, is an inner view of the front or charging end of the machine.

Fig. 7, is a detached perspective view of one of the baffles or aprons of the charging chute.

Fig. 8, is a detached perspective view of a pair of the deflectors which form the charging pockets of the machine.

Fig. 9, is a side view of a portion of one of said deflectors illustrating a swinging gate thereon.

Fig. 10, is a fragmental sectional view of a portion of the end of the drum showing a modification in the construction of the charging chute.

Fig. 11, is a perspective view partly in section of the charging end of the drum and the charging chute showing a modification in the construction of the drum, the section being taken on line 11—11, of Fig. 12, looking in the direction indicated by the arrows.

Fig. 12, is an inner view of the front or charging end of the drum embodying the construction shown in Fig. 11, but with the charging chute omitted.

Fig. 13, is a sectional view of a portion of the front end of the drum embodying the modification shown in Fig. 11, and illustrating the deflecting chute leading from one of the flanges of the drum to and through the other flange thereof.

Fig. 14, is a fragmental view of similar parts, and

Fig. 15, is a similar view showing a modification in the construction of the deflecting chute.

Corresponding numerals of reference refer to like parts throughout the different views of the drawings.

While I have shown in Fig. 1, of the drawings, a view partly in section and partly in perspective, of a mixing machine having two compartments, that is, a receiving and

- mixing chamber, and a storage chamber, yet my present invention relates to the charging or feeding end of the machine and the mechanism employed in connection therewith and 5 for this reason the description of the apparatus will be restricted mainly to said portion and said mechanism, reference being had to the other parts of the machine in a general way only.
- 10 The reference numeral 12, designates the mixing receptacle which is cylindrical in shape and may be suitably mounted for rotation, but is shown in Fig. 1, of the drawings, as being provided with bandlike or circular gears 13, one of which is located on the outer surface of the drum or receptacle 12, near each of its ends and are adapted to engage gears on a driven shaft or shafts, not shown, which may be journaled on the supporting frame for the drum, which frame may be of the ordinary or any suitable construction, and is also not shown. The front or charging end of the drum 12, is provided with an inwardly extended annular flange 14 in the form of an apertured disk, and the opposite or discharging end of the drum is provided with a head 15, through a suitable opening in which leads a discharging chute 16, which is tapered forwardly as shown.
- 20 Horizontally located at or near the front end of the drum is a platform 17, on which wheelbarrows containing the different kinds of materials to be mixed, may be trundled in order that their loads may be dumped into the mixing receptacle or drum. Extended upwardly from the platform 17, is an upright board or plate 18, which is located transversely with respect to the front end of the drum 12, and at a slight distance forwardly therefrom, and has in its upper portion a segmental recess 19, to receive a curved piece or sheet 20, of metal or other suitable material which is provided at each of its edges with an upwardly and outwardly inclined portion 21, each of which is provided at its rear edge with an upwardly extended flange 22, which flanges rest against or approximate the front surface of the flange 14, of the drum. The 30 curved piece 20, is extended through the opening 23, of the flange 14, of the drum and some distance rearwardly of said flange as is clearly shown in different views of the drawings, and lies directly above the lower portion of the inner periphery of said flange. Located on the front or outer portion of the curved piece 20, is a segmental plate or board 24, from the upper edge of which is extended rearwardly and downwardly a 40 chute plate 25, which is secured at its lower edge to the rear edge of the piece 20, and in conjunction with said piece and with the uprights 18, and 24, form the charging chute of the machine, into the outer or front portion of which the material can be readily dumped from wheelbarrows trundled on the platform 17, therefor. Secured on the lower surface of the curved piece 20, of the charging chute and within the receptacle 12, and near the inner surface of the flange 14, 70 thereof, is a segmental apron or baffle plate 26, which extends in parallelism with said flange and upwardly some distance above that side of the chute plate 25, in the direction of the rotation of the drum, as will be readily understood by reference to Figs. 2, 5, and 6, of the drawings. Inwardly of the baffle plate or apron 26, and at a slight distance therefrom, the curved portion 20, of the chute has mounted thereon another segmental baffle or apron 27, which is extended upwardly on one side of the chute plate 25, and in a corresponding direction with the plate or apron 26, but the last named apron terminates at its lower end at about the middle of the curved piece 20, as will be readily understood by reference to Fig. 6, of the drawings. The baffle plate or apron 27, is provided on its rear surface with one or more rearwardly extended wings 28, which 80 are located at angles to the baffle or apron 27, and are inclined rearwardly in the direction of the rotation of the drum.
- 45 As shown in Figs. 1, and 5, of the drawings, the drum 12, has secured thereto, near the flange 14, thereof, a series of overlapping, diagonally, arranged deflectors 29, which are of a greater width than the front flange 14, which are extended from points at suitable distances apart rearwardly from the flange 14, and have their front ends disposed at a slight distance from said flange. These deflectors or plates may be secured to the inner surface of the drum 12, by means of angle brackets 30, and are spaced apart, 100 and have substantially the same diagonal inclination toward the rear portion of the drum thus forming circularly arranged pockets or chutes which have a tendency to cause the material to advance into the drum. 110 Between each of the deflectors or plates 29, and the one adjacent thereto is pivotally mounted at its inner portion a door or gate 31, which are adapted to swing in the opposite direction of the rotation of the drum so as to permit the material to pass freely through the charging pockets formed by the deflectors or plates 29, but in the event of the backward movement of said material, that is, toward the charging end of the drum, said gates or doors will be moved forwardly thereby until they are stopped in such movement by means of projections 32, on the outer portions of the plates 29, or deflectors.
- 55 The drum 12, may be provided at about its middle with a transversely disposed partition 33, to divide it into two chambers, and said partition has a hinged door 34, to close a doorway 35, in said partition 120

through which the mixture passes from the mixing chamber to the storage or discharging chamber, but said elements form no part of my present invention, and for this 5 reason they will not be herein further referred to.

Instead of providing the circular piece 20, of the chute with a pair of baffle plates or aprons 26, and 27, as shown in Figs. 1, 10 to 6 inclusive, and above described, I may employ a single baffle plate or apron 27^a, mounted on the rear lower portion of the part 20, as shown in Fig. 10, of the drawings, which baffle plate or apron may be 15 provided on its upper and rear surface with angularly disposed and rearwardly extended wings 28, (see Fig. 7,) if desired.

In some instances I may provide the charging end of the drum 12, with an additional or supplemental inwardly extended flange 36, as shown in Figs. 11, to 15, inclusive of the drawings, which flange is located on and secured to the inner peripheral wall of the drum 12, at a slight distance rearwardly of the flange 14, and in parallelism therewith. When employing this construction the charging chute is extended rearwardly within the lower portions of the openings in the flanges 14, and 36, 30 so as to project a slight distance rearwardly within the drum from the latter named flange as is clearly shown in Fig. 11, of the drawings, but so as to lie closely to the inner peripheries of said flanges. The portion 20, of the charging chute, in the construction now under consideration, is provided with a segmental baffle plate 26^a, which extends downwardly from the portion 20, about midway between the flanges 40 14, and 36, of the drum, and lies in parallelism therewith. Extended diagonally from the rear surface of the flange 14, and inwardly from the peripheral wall of the drum 12, is a plate 37, which is joined at 45 its rear end to one edge of an opening 38, in the flange 36, which arrangement will provide a deflecting chute for any material that may fall or pass into the space between the flanges 14, and 36, of the drum. The 50 upper edge of the plate 37, may have extended therefrom in the direction of the movement of the drum a hood 39, which will serve to assist in guiding the material from the space between said flanges, but it 55 is obvious that this hood may be omitted as shown in Fig. 15, of the drawings.

From the foregoing and by reference to the drawings it will be readily understood and clearly seen, that as the drum 12, is 60 rotated in the direction indicated by the arrows shown in continuous lines in Figs. 1, 13, to 15, inclusive, of the drawings, the material placed therein by way of the charging chute will fall into the charging pockets formed by the deflectors or plates 29,

and will thereby be directed rearwardly of the drum. However, as the material while being mixed, is in a slushy state, it will have a tendency when considerable material is held in the drum, to work out through the 70 space between the charging chute and the inner periphery of the flange 14, when only one flange on the drum is employed, and between the peripheries of the flanges 14, and 36, when the construction shown in 75 Figs. 11, to 15, is employed, and to obviate this, the baffle plates 26, and 27, when the construction shown in Figs. 1, 3, 4, 5, and 6, is used, are employed, and when the construction illustrated in Fig. 10 is used, the 80 baffle plate or apron 27^a, is employed for this purpose, and when the construction illustrated in Figs. 11, to 15, inclusive is used, the baffle plate or apron 26^a, and the deflecting chute 37, is employed for the 85 same purpose, for it is apparent that as the material rotates with or is carried up by the drum the rearwardly directed wings 28, in the first named construction, will again force it rearwardly into the charging pockets formed by the plates 29, or deflectors. In the rotation of the drum indicated by the arrows in continuous lines in Figs. 13, to 15, inclusive, it will be understood that the 90 material which is carried up by the drum will have a tendency to move therein, in the direction indicated by the arrows in dotted lines in said figures, so that the material which may pass or find its way into the space between the flanges 14, and 36, of the drum will be deflected by means of the baffle plate or apron 26^a, and be caused to pass from said space rearwardly into the 95 drum by reason of the deflecting chute 37, which is located between said flanges. 100

Having thus fully described my invention what I claim as new and desire to secure by Letters Patent is—

1. In a mixer, in combination, a revoluble drum having an annular front end wall, 110 means therein to mix and agitate the materials, and a low charging device consisting of blades of a greater width, than the front end wall of the drum from the opening therein to the periphery, said blades overlapping at their inner ends, forming a receiving means in front of a charging means and also upon revolution of the drum, a retaining means. 115

2. In a mixer, in combination, a revoluble drum, having at its front end, two inwardly extending annular flanges, and a continuous series of blades, having their front portions, of a greater height, than said flange, said blades being set at an angle from and running rearwardly for a short distance, said blades being spaced apart forming a channel, so as to charge and retain the material in the drum. 125

3. In a mixer, in combination, a revoluble 130

drum, means therein to mix the material, a low charging device consisting of an inwardly extending annular flange and a series of blades extending from a short distance from said flange and set at an angle to the axis of the receptacle, and extending backwardly for a short distance for the purpose of directing the material into the receptacle, said blades running parallel with each other for a short distance, and a gate mounted between said blades, said gate having a free swinging movement in one direction only and restricted in the other direction for the purpose of stopping the return flow of loose concrete.

4. In a mixer, in combination, a revolute drum, having on its front end, two inwardly extending annular flanges, the rear flange having openings adjacent to the drum for the return of overflow material.

5. In a mixer, in combination, a revolute drum, having on its front end, two inwardly extending annular flanges, the rear flange having openings adjacent to the drum for the return of overflow material, and a blade extending from one side of the opening in the rear flange, at an angle to the axis and forwardly to the one side of the first flange for the purpose to guide overflow material.

6. In a mixer, in combination, a revolute drum, having on its front end, two inwardly extending annular flanges, the rear flange having openings adjacent to the drum for the return of overflow material, and a blade

extending from one side of the opening in the rear flange, at an angle to the axis and forwardly to the one side of the first flange for the purpose of guiding overflow material back into the mixer, and a charging chute

extending rearwardly and inwardly over 40 said flanges, and allowing clearance between the flange and the chute and a flange attached to the lower side of the chute and extending outwardly between the flanges.

7. A rotary mixing receptacle, having at 45 its receiving end a charging device comprising of a centrally apertured disk secured to the receptacle and having a flange extending inwardly of the receptacle, and a series of blades, extending at their front ends near 50 said flange, the blades at their front end being of a greater width than the disk from the opening therein to its periphery, said blades over-lapping sufficiently to form protecting walls for the material being charged 55 and retaining walls for the material already in the drum upon rotation of the drum.

8. In a mixer, in combination, a revolute drum, having means to discharge the mixed material, and a charging device, comprising 60 of narrow flanges in combination with wide blades.

9. In a mixer, in combination, a revolute drum having two inwardly extending flanges at its receiving end, the rear one of 65 said flanges having a series of openings peripherally arranged therein with blades extending, at an angle to the axis of the receptacle, from one side of the openings forwardly to the first flange, and a charging 70 device, consisting of blades, being of a greater height than said flanges at their front portions.
